UNITED STATES PATENT OFFICE.

WILLIAM J. KENNEY, OF WILMETTE, ILLINOIS, ASSIGNOR TO UNDERFEED STOKER COMPANY OF AMERICA, OF CHICAGO, ILLINOIS, A CORPORATION OF NEW JERSEY.

UNDERFEED STOKER.

1,196,869.

Specification of Letters Patent. Patented Sept. 5, 1916.

Application filed April 11, 1912. Serial No. 690,154.

To all whom it may concern:

Be it known that I, WILLIAM J. KENNEY, a citizen of the United States, residing at Wilmette, county of Cook, State of Illinois, 5 have invented a certain new and useful Improvement in Underfeed Stokers, and declare the following to be a full, clear, and exact description of the same, such as will enable others skilled in the art to which it 10 pertains to make and use the same, reference being had to the accompanying drawings, which form a part of this specification.

My invention relates to the type of underfeed stoker described and claimed in the 15 Kenney and Grohn Patent No. 1,018,976 and has for its object to improve the same and increase its efficiency.

The various features of novelty whereby 20 my invention is characterized will hereinafter be pointed out with particularity in the claims; but, for a full understanding of my invention and of its various objects and advantages, reference may be had to the following detailed description taken in connection with the accompanying drawings, 25 wherein:

Figure 1 is a vertical section through a furnace arranged in accordance with a preferred form of my invention; Fig. 2 is a 30 horizontal section through the furnace above the retort and dead plates, the dead plate on one side of the retort being removed to show the underlying mechanism; and Fig. 3 is a detail on a larger scale of one of the 35 dogs and the adjacent portion of the dead plate which supports it.

Referring to the drawings, 1 represents a furnace of any suitable construction in 40 which is contained a retort 2. At the sides and in rear of the retort are stationary dead plates 3 and 4, respectively, which, with the retort, divide the furnace into an upper combustion chamber and a lower air chamber. Fuel is supplied to the retort by means of a 45 steam-operated ram 5 which forces fuel delivered from the lower end of the hopper 6 into the front end of the retort. The ram is provided with a pusher rod 7 which extends longitudinally through the retort near 50 the bottom thereof and serves to carry the fuel toward the rear. In stokers of this kind the fuel is caused to rise through the top of the retort where it is consumed and then swells out upon the dead plates at the sides,

the lifting of the fuel being effected by the 55 pressure of the ram and the pusher rod in the longitudinal direction. Various factors therefore enter into the design of the retort in order to produce an even distribution of the fuel through the length of the retort, 60 the most satisfactory expedient for securing this uniform distribution being a gradual decrease in the depth of the retort from the front end toward the rear. Where the clinkers and ashes are fed automatically 65 back over the dead plates it is desirable to have some drop from the front toward the back of the furnace so as to permit gravity to assist in moving the clinkers and ashes. I have found after long experimentation that 70 the most successful results are obtained by so proportioning and positioning the retort that a total angle of convergence of about six degrees from the front to the back is divided between an upward inclination of 75 about three degrees in the bottom of the retort and a downward inclination of like amount in the top of the retort. This arrangement insures an even distribution of the fuel and at the same time permits the 80 clinkers and ashes to move freely from the front toward the back under the influence of the dogs to be hereinafter described.

In each of the side dead plates are one or 85 more rows of oscillatory dogs 8 having arms 9 which project down below the dead plates, and noses 10 which are adapted to swing up and back from positions in the plane of the dead plates, thereby breaking the clinkers and ashes from the sides of the retort and 90 feeding them toward the rear. The downwardly projecting arms of each row of dogs are connected together by a longitudinal bar which causes them to move in unison with each other. Extending transversely beneath the retort is a rock shaft 12 having an upwardly projecting rocker arm 13 in the vicinity of each of the links or bars 11. The upper end of each rocker arm is secured to the rear end of one of the links or bars by 100 means of a longitudinally adjustable connecting rod 14. In the arrangement shown, each connecting rod is made in two pieces joined by a turn buckle 15. By this means the normal angular positions of the dogs 105 may be adjusted so as to vary the effective length of the upward and backward stroke of the noses of the dogs. This is extremely

advantageous since it permits each stoker to be adjusted accurately to suit the particular conditions of service, the effective lengths of the strokes of the dogs being varied according to the quality and character of the coal in each particular installation. The rock shaft may conveniently be actuated by a steam engine 16 comprising a piston movable in a suitable cylinder and having a connecting rod 17 secured to one end of an arm 18 extending radially from the rock shaft. I am also enabled to produce another result through the adjustment of the dogs. In stokers of this kind more or less of the air from the air chamber passes up around the dogs through the openings in the dead plates in which the dogs lie; such air aiding in the combustion of any unconsumed fuel which reaches the dead plates. I so shape the openings and the dogs that the space through which air can pass up around the dogs in the normal position of rest may be varied by the adjustment of the dogs in the manner heretofore described; thus controlling the flow of air through the dead plates and into the hot mass lying thereon. This feature will best be understood from an examination of Fig. 3. The upper rear corner, 40, of each dog is in the form of a segment of a cylinder having its axis coincident with the pivotal axis, 41, of the dog. The front edge or face, 42, of the dog is also a segment of a cylinder having its axis at the pivotal axis of the dog. The opening 43 in which the dog lies has its front and rear edges 44 and 45, respectively, curved eccentrically to the pivotal axis of the dog; the arrangement being such that as the tip 46 of the nose of the dog travels vertically through the dead plate, the distance therefrom to the front edge 44 of the opening varies, this being also true with respect to the extreme rear end, 47, of the dog and the rear edge, 45, of the opening. Consequently, by shifting the dog slightly when in its position of rest, the effective area of the air passages adjacent thereto and the amount of air passing up past the dog may be varied.

Assuming that Fig. 3 shows the position of rest of one of the dogs: Then by adjusting the turnbuckles to shorten the connecting rods slightly, all of the dogs are turned through a small angle in the clockwise direction, decreasing the size of the air passages; while upon adjusting the turn buckles so as to lengthen the connecting rods slightly, the dogs are shifted in the counter-clockwise direction and the area of the air passages is increased.

It will of course be understood that the curvature of the dogs and of the edges of the openings in which they lie need not be just as illustrated and that my invention contemplates any arrangement for varying the air passages adjacent to the dogs upon

adjusting the dogs in one direction or the other.

At the rear end of the dead plates is a discharge chute or passage 19 into which the clinkers and ashes fall as they are pushed over the rear edge of the dead plates. The top of the discharge chute is normally covered by a perforated clinker breaker 20 which is preferably supported upon a transverse oscillatory shaft 21 and has its upper surface in the form of an arc of a circle with its center at the axis of the shaft 21. Furthermore, the segmental clinker breaker is preferably connected at its front edge to the upper end of a transverse wing or plate 23 along the rear edge of the dead plate to cut or break off any considerable mass of clinker which may overhang the discharge chute without falling into it. Normally the clinker breaker occupies the position shown in the drawings and the clinkers and ashes, as they are fed back, collect upon it. By oscillating the shaft 21 in the clockwise direction, the clinker breaker is swung back out of the way and the overlying mass of clinkers and ashes is scraped from it into the discharge chute by an overhanging portion of the bridge wall 24. The supporting shaft for the clinker breaker may be actuated in any suitable manner, conveniently by means of a connecting rod 25 secured at its rear end to a crank arm 26 on the shaft and adapted to be connected at its front end to the rocker arm 18. Thus when the main rock shaft 12 is oscillated to move the oscillating dogs, the clinker breaker is also oscillated so as to permit the clinkers and ashes to be dumped as they reach the back of the furnace. It is not necessary to move the clinker breaker at each operation of the dogs and, in fact, it is desirable to permit the hot ashes to pile up to some extent on the clinker breaker, permitting them to give off some of the heat which they still contain; therefore, I have provided means for disconnecting the connecting rod 25 from the rocker arm 18 at will. In the arrangement shown, the front end of the connecting rod 25 is made in the form of a fork within which the rocker arm 18 lies. In the underside of the front ends of the prongs of the fork are notches 28 adapted to receive pins 29 projecting laterally from the rocker arm 18.

30 is a lever suitably supported between its ends so as to have one end projecting into proximity to the front end of the connecting rod 25, and on the connecting rod is a pin 31 which is adapted to be engaged by the adjacent end of the lever so as to permit the connecting rod to be lifted clear of the pin on the rocker arm, as indicated in Fig. 130

1. When the parts are in this condition, the rocker arm may swing back and forth without affecting the connecting rod 25. When the lever 30 is oscillated so as to lower 5 the front end of the connecting rod, the pins on the rocker arm will drop into the notches on the connecting rod and the connecting rod will be reciprocated by the rocker arm. The lever 30 may conveniently be operated 10 by means of a hand lever 32 projecting above the floor in front of the furnace and connected to the lever 30 by a suitable link 33. By manipulating the lever 32, the man in charge of the furnace may cause the ashes 15 to be dumped whenever it is desirable, the clinker breaker remaining stationary at other times and permitting the clinkers and ashes to accumulate thereon.

It may sometimes happen that there will 20 be a little unconsumed or only partially consumed fuel among the clinkers and ashes when they reach the clinker breaker and pile up thereon, and I have therefore provided means whereby air may be caused to 25 flow up through the clinker breaker and through the clinkers and ashes so as to complete the combustion of any combustible matter remaining therein. This I accomplish by means of a conduit 50 leading from 30 the air chamber beneath the retort into the ash chute at a point below the clinker breaker, together with a valve 51 which may be controlled by a suitable handle 52 extending to the outside of the furnace. The air 35 chamber is supplied with air from a suitable blower, indicated conventionally at 53, in the usual way so that a static pressure is maintained therein. The bulk of this air passes up through the usual twyer blocks 54, 40 some of it through the spaces in the dead plates around the dogs, and some of it, when the valve 51 is wholly or partially open, through the perforated clinker breaker. Thus the fuel is positively supplied with 45 air from the time combustion begins to the time the waste clinkers and ashes are discharged, and the possibility of fuel passing through the furnace in an unconsumed condition is reduced to a minimum.

50 While I have illustrated and described only a single preferred form of my invention, I do not desire to be limited to the particular structural details thus illustrated and described; but intend to cover all forms and arrangements which fall within the terms employed in the definitions of my invention constituting the appended claims.

I claim:

60 1. In combination, a furnace, a retort in the furnace, dead plates at the sides of the retort for receiving clinkers and ashes therefrom, said dead plates being provided with openings therethrough, dogs mounted in said openings so as to be movable from a position of rest upwardly and rearwardly

to break up the clinkers and ashes and carry them toward the rear, operating mechanism for said dogs, means for adjusting said mechanism to adjust the position of rest of said dogs, the dogs and the openings in 70 which they lie being so constructed and arranged as to vary the clearance between the dogs and the edges of the openings upon a variation in the position of rest of the dogs, and means for introducing air under pressure beneath the dead plates. 75

2. In combination, a furnace, a retort in the furnace, dead plates at the sides of the retort for receiving clinkers and ashes therefrom, said dead plates coöperating with the 80 retort to divide the furnace into an upper combustion chamber and a lower air chamber, twyer blocks arranged at the top of the retort and communicating with said air chamber for introducing into the air chamber sufficient air under pressure to support combustion, said dead plates having openings therethrough for permitting air to pass from the air chamber into the combustion chamber, and means for adjusting the size 90 of said openings.

3. In combination, a furnace, a retort in the furnace, dead plates at the sides of the retort for receiving clinkers and ashes therefrom, the retort and the dead plates 95 dividing the furnace into an upper combustion chamber and a lower air chamber, twyer blocks on the retort for admitting air from the air chamber, there being a discharge chute for ashes at one end of the retort, a perforated clinker breaker at the upper end of said ash chute, and means for introducing air under pressure into said air chamber and into the ash chute at a point beneath said clinker breaker. 100

4. In combination, a furnace, a retort in the furnace, dead plates at the sides of the retort for receiving clinkers and ashes therefrom, the retort and the dead plates dividing the furnace into an upper combustion chamber and a lower air chamber, twyer blocks on the retort for admitting air from the air chamber, there being a discharge chute for ashes at one end of the retort, a perforated clinker breaker at the upper end of said ash chute, means for delivering air under pressure to said air chamber, and a conduit leading from said air chamber into the ash chute at a point beneath said clinker breaker. 115

5. In combination, a furnace, a retort in the furnace, dead plates at the sides of the retort for receiving clinkers and ashes therefrom, the retort and the dead plates dividing the furnace into an upper combustion chamber and a lower air chamber, twyer blocks on the retort for admitting air from the air chamber, there being a discharge chute for ashes at one end of the retort, a 125 perforated clinker breaker at the upper end

of said ash chute, means for introducing air under pressure into said air chamber, a conduit leading from the air chamber and opening into the ash chute at a point beneath said clinker breaker, and a valve for controlling the passage of air through said conduit.

In testimony whereof, I, sign this specification in the presence of two witnesses.

WILLIAM J. KENNEY.
